US0D1110054S

(12) United States Design Patent (10) Patent No.: US D1,110,054 S
(45) Date of Patent:  Jan. 27, 2026

(54) CHAIR

(71) Applicant: VICCARBE HABITAT, S.L.,
Beniparrell (ES)

(72) Inventors: Ludovica Desideria Pozzi Serafini,
Milan (IT); Roberto Palomba, Milan
(IT)

(73) Assignee: VICCARBE HABITAT, S.L.,
Beniparrell (ES)

() Term: 15 Years

(21) Appl. No.: 29/968,189

(22) Filed: Oct. 15, 2024

(30) Foreign Application Priority Data

Apr. 17, 2024 (EM) 015057922-0007

(51) LOC (15) Cl. 06-01

(52) U.S. Cl.
USPC D6/375

(58) Field of Classification Search
USPC D6/334, 366, 370, 373, 374, 375, 376,
